United States Patent Office

Des. 181,120
Patented Oct. 8, 1957

181,120

DISPLAY CABINET OR SIMILAR ARTICLE

Oliver Boza, Euclid, Ohio, assignor to The Weatherhead Company, Cleveland, Ohio, a corporation of Ohio

Application April 25, 1956, Serial No. 41,208

Term of patent 14 years

(Cl. D80—9)

The figure is a front perspective view of a display cabinet showing my new design, one drawer being pulled out for the purpose of illustration. The rear of the display cabinet is substantially plain. The right hand side, not shown, is plain.

I claim:

The ornamental design for a display cabinet or similar article as shown and described.
